PLASTIC DRAPERY

Bernard J. Sadoff, Jr., 11801 Paso Robles Ave., Granada Hills, Calif., and Gerald D. Appel, 17813 Malden, Northridge, Calif.

Filed Feb. 11, 1964, Ser. No. 78,816

Term of patent 14 years

(Cl. D54—2)

FIG. 1.

FIG. 2.

FIG. 5

FIG. 4.

FIG. 3.

FIG. 1 is a perspective view of a portion of a plastic drapery embodying our invention;

FIG. 2 is a top plan view of a plastic drapery embodying our invention;

FIG. 3 is a section view taken on line 3-3 of FIG. 1;

FIG. 4 is a perspective view of a portion of an alternative form of drapery embodying the design of our invention;

FIG. 5 is a vertical sectional view of the drapery of FIG. 4 taken along the plane indicated at 5-5 in FIG. 4.

The drapery which is shown complete in FIG. 2 has been broken away in FIGS. 1 and 4 to indicate an article of indeterminate length and height.

We claim:

The ornamental design for a plastic drapery, substantially as shown and described.
